US0D1063491S

(12) United States Design Patent (10) Patent No.: US D1,063,491 S
(45) Date of Patent: * Feb. 25, 2025

(54) COOKING POT INCLUDING FOR CAMPING

(71) Applicant: Fissler GmbH, Idar-Oberstein (DE)

(72) Inventor: Tim Konetzka, Augsburg (DE)

() Term: 15 Years

(21) Appl. No.: 35/519,228

(22) Filed: Nov. 17, 2023

(80) Hague Agreement Data

Int. Filing Date: Nov. 17, 2023

Int. Reg. No.: DM/233354

Int. Reg. Date: Nov. 17, 2023

Int. Reg. Pub. Date: Dec. 1, 2023

(30) Foreign Application Priority Data
